UNITED STATES PATENT OFFICE.

REUBEN B. BENJAMIN AND ERNST G. K. ANDERSON, OF CHICAGO, ILLINOIS, ASSIGNEES
TO BENJAMIN ELECTRIC MANUFACTURING COMPANY, OF CHICAGO, ILLINOIS, A
CORPORATION OF ILLINOIS.

FUSE-PLUG.

1,316,671.

Specification of Letters Patent. Patented Sept. 23, 1919.

Application filed May 2, 1916. Serial No. 94,864.

To all whom it may concern:

Be it known that we, REUBEN B. BENJAMIN and ERNST G. K. ANDERSON, both citizens of the United States, residing at Chicago, in the county of Cook and State of Illinois, have jointly invented new and useful Improvements in Fuse-Plugs, of which the following is a full, clear, concise, and exact description, reference being had to the accompanying drawings, forming a part of this specification.

Our invention relates to fuse plugs, and more particularly to fuse plugs provided with a plurality of fuses which can be successively brought into the circuit.

One of the objects of our invention is to provide an improved fuse plug which shall be simple in construction, efficient in use and easy to manufacture.

20 Further objects will appear from the detailed description to follow taken in connection with the appended claims.

In the drawings, in which we have shown two embodiments of our invention;

25 Figure 1 is an axial section of the fuse plug;

Fig. 2 is a transverse section on the line 2—2 of Fig. 1;

30 Fig. 3 is a transverse section on the line 3—3 of Fig. 1;

Fig. 4 is a plan view of a disk or washer for engaging the ends of the fuses;

35 Fig. 5 is a side elevation of another form of magazine fuse plug embodying our invention;

Fig. 6 is an axial section of the plug shown in Fig. 5, substantially on the line 6—6 of Fig. 8;

40 Fig. 7 is a section on the line 7—7 of Fig. 6;

Fig. 8 is a section on the line 8—8 of Fig. 6;

Fig. 9 is a section on the line 9—9 of Fig. 6;

45 Fig. 10 is a side elevation of the insulating base;

Fig. 11 is a detail view of part of the shell contact; and

50 Fig. 12 is a detail view of a grooved disk with the fuses engaged.

Referring now to the drawing in detail, and first to Figs. 1 to 5 inclusive, the plug here shown comprises an insulating base 10, shell and center contacts 11 and 12 support-

ed by the insulating base, a plurality of 55 fuses 13 also supported by the insulating base, a closure member 14 which may be of mica for preventing the escape of the burnt gases, a retaining ring or cap 15 for holding the closure 14 in position, an insulating 60 sleeve 15^a surrounding the outer end of the shell contact for insulating the shell contact from the retaining ring 15, and a closure member 16 which may be of mica located in the inner end of the plug to hinder the escape 65 of the burnt gases.

The bent over ends 16^a of the fuses 13 are clamped between an eyelet 17 and a grooved disk 18. The center contact 12 extends through the eyelet 17 and grooved disk 18 70 and has its outer end flanged over to firmly clamp the fuse ends 16^a between the eyelet 17 and grooved disk. The eyelet 17 also serves to hold the mica disk or closure 16 in place. The insulating base 10 has a plurality of recesses or grooves 27 in its side for engagement with the spring tongues 20 secured to the shell contact 11 which may be formed integral therewith. The fuses 13 are located in passages 21 in the insulating base and their outer ends extend through eyelets 23 to which they are secured by being swaged over as indicated at 24. The shell contact 11 has a tongue 25 formed integral therewith which extends inwardly 80 in position to be engaged by the eyelets 23 and the ends of the fuses 13. The retaining ring 15 has a flange portion 28 integral therewith which is beaded over a corresponding bead 29 on the shell contact. 90

The circuit through the plug is from the shell contact 11 through the contact tongue 25, fuse 13 and eyelet 17 to the center contact 12. When one of the fuses has blown and it is desired to bring a new fuse in position the insulating base 10 is withdrawn from the shell contact 11 until the tongue 20 is out of engagement with the groove 19. The base 10 is then rotated with respect to the shell until another one of the grooves 19 95 is in position to receive the tongue 20. The base is then pushed into the shell until the eyelet 23 engages the contact tongue 25. As the closures 14 and 16 are mica it can be determined by inspection which of the 100 fuses have been blown.

The plug shown in Figs. 5 to 12, inclusive, comprises an insulating base 30, a shell con-

tact 31 surrounding the base 30 and supported thereby, a center contact 32 preferably a sheet metal eyelet, and a plurality of fuses 33 electrically connected to the center contact 32 to be successively brought into electrical connection with the shell contact 31.

The base 30 is provided with a plurality of longitudinally extending grooves 34 in which the fuses 33 extend. To prevent short circuiting between the fuses and the shell contact an insulating sleeve 35 is provided which closely surrounds the base 30 and covers the grooves 34. To position this sleeve 35 on the base the latter is provided with a shoulder 36 with which the lower edge of the sleeve engages. The grooves 34 extend somewhat below the sleeve 35 and thus provide passage for the escape of the gases from the grooves to the space between the shell contact 31 and the sleeve 35 of the base 30. The grooves 34 are also in communication with a central recess 36 in the base 30 through openings 36^a providing still another passage for the escape of the burnt gases.

The upper ends of all the grooves 34 are closed by an insulating disk 37. To hold the disk 37 in place and to electrically connect the fuses with the center contact a grooved plate 38 and eyelet 39 are provided between which the fuses are clamped. The plate is provided with radial grooves 40 (Fig. 12) in which the bent over ends 41 of the fuses lie. The eyelet 39 is provided with flanges 42 and 43 which embrace the inner edge of the disk 37. The lower ends of the fuses are connected with metal eyelets 44 which eyelets are secured in openings in the base 30.

To make the electrical connection with the fuses 33 the shell contact 31 is provided with an inwardly extending contact piece 45 which is located in position to be successively engaged by the eyelets 44 to which the fuses are electrically and mechanically connected. To properly position the base 30 with respect to the shell 31 the base is provided with a plurality of grooves or recesses 46 to receive a lug 47 (Figs. 7 and 11) struck up from the shell contact. To retain the base 30 within the shell 31 the shell is provided with a pair of spring fingers 48 struck up from the material of the shell for engagement with the recesses 46 in the base 30. These fingers will prevent the base from dropping out of the shell but will permit the base to be readily withdrawn when desired.

To prevent the escape of the burnt gases at the outer end of the plug an insulating disk 49 extends across the base 30 and is held in place by means of a metal cap 50 provided with a flange 51 which is beaded over a corresponding bead 52 on the shell 31. A sleeve 53 of fiber or other suitable insulating ma-

terial is provided between the shell 31 and the flange 51 and this sleeve 53 also extends inwardly up to the threaded portion of the shell 31 to prevent accidental contact with the charged parts when the plug is screwed into a receptacle.

The use of this plug is substantially the same as that of the form shown in Figs. 1, 2, 3 and 4. The circuit is from the center contact 32 through the eyelet 39 and through the plate 40 to one of the fuses 33 and through the contact piece 45 to the shell contact 31. After a fuse has been blown the plug is unscrewed from the receptacle and the base 30 is partly withdrawn from the shell contact 31 and rotated to bring a new fuse into position to register with the contact piece 45. The base 30 is then slipped back into the shell 31 to bring the fuse 33 into electrical connection with the shell contact.

To determine which of the fuses have been blown, all that is necessary is to screw the plug out of the receptacle and withdraw the base 30 from the shell 31, when the condition of the fuses can be determined by inspection, through the openings below the sleeve 35.

Having thus described our invention what we claim as new and desire to secure by Letters Patent is:—

1. A magazine fuse plug comprising an insulating base, a plurality of fuses supported thereby, a shell contact surrounding said base, said base being movable with respect to said shell to successively bring said fuses into electrical connection with said shell contact, and an insulating disk closure extending across one end of said insulating base and one end of said shell contact, said shell contact having a bead thereon and means for securing said closure to said shell contact comprising a cap having a flange beaded over said first bead.

2. A magazine fuse plug comprising an insulating base, a plurality of fuses supported thereby, a shell contact surrounding said base, said base being movable with respect to said shell to successively bring said fuses into electrical connection with said shell contact, and an insulating disk closure extending across one end of said insulating base and one end of said shell contact and secured to said shell contact, and a thin insulating sleeve immediately surrounding the end of said shell contact adjacent said disk closure.

3. A magazine fuse plug comprising a threaded shell contact, an insulating base, a plurality of fuses supported thereby, a cap closing the outer end of the fuse plug, said base being insertible within said shell contact from the inner end of the fuse plug and being movable with respect to said shell to successively bring said fuses into electrical

connection with said shell contact, and spring means for holding said base in said shell comprising a spring tongue extending substantially parallel to the axis of the fuse plug.

4. A magazine fuse plug comprising a threaded shell contact, an insulating base, a plurality of fuses supported thereby, a cap closing the outer end of the fuse plug, said base being insertible within said shell contact from the inner end of the fuse plug and being movable with respect to said shell to successively bring said fuses into electrical connection with said shell contact, and spring means for holding said base in said shell comprising a spring tongue extending substantially parallel to the axis of the fuse plug and secured to said shell contact, said base having a plurality of grooves extending substantially parallel to the axis of the fuse plug with any one of which said spring tongue may engage.

5. A magazine fuse plug comprising an insulating base, a plurality of fuses supported thereby, and means for securing the ends of said fuses comprising a metal disk having a plurality of grooves therein radiating from a common center to receive the ends of said fuses, said disk having a central opening therein, and a center contact member extending through said opening and secured to said base and electrically connected with said disk.

6. A magazine fuse plug comprising a substantially cylindrical insulating base having a plurality of longitudinally extending grooves, fuses extending longitudinally of said grooves, an insulating sleeve surrounding said base for covering said grooves, an insulating disk extending across the side of said base for closing the ends of said grooves, and an eyelet for securing said disk to said base and serving as an electric contact.

7. A magazine fuse plug comprising an insulating base, a center contact supported at the inner end of said base, a shell contact surrounding said base, a conductor electrically connected to said shell contact extending inwardly at the outer end of the base, a plurality of fuses electrically connected to said center contact and movable successively into electrical connection with said conductor, and a thin insulating disk closure extending across the outer end of said base and secured to said shell contact.

8. A magazine fuse plug comprising an insulating base, a center contact supported at the inner end of said base, a shell contact surrounding said base, a conductor electrically connected to said shell contact extending inwardly at the outer end of the base, a

plurality of fuses electrically connected to said center contact and movable successively into electrical connection with said conductor, and a thin insulating disk closure extending across the outer end of said base, and means for securing said disk to said shell contact comprising a cap inclosing said disk and secured to said shell contact.

9. A magazine fuse plug comprising an insulating base, a center contact supported at the inner end of said base, a shell contact surrounding said base, a conductor electrically connected to said shell contact extending inwardly at the outer end of the base, a plurality of fuses electrically connected to said center contact and movable successively into electrical connection with said conductor, and a thin insulating disk closure extending across the outer end of said base, and means for securing said disk to said shell contact comprising a cap inclosing said disk and secured to said shell contact, and an insulating sleeve immediately surrounding the end of the shell contact for insulating said cap from said shell contact.

10. A magazine fuse plug comprising an insulating base, a center contact supported at the inner end of said base, a shell contact surrounding said base, a conductor electrically connected to said shell contact extending inwardly at the outer end of the base, a plurality of fuses electrically connected to said center contact and movable successively into electrical connection with said conductor, and a thin insulating disk closure extending across the outer end of said base, means for securing said disk to said shell contact comprising a cap inclosing said disk and secured to said shell contact, and an insulating sleeve immediately surrounding the end of the shell contact for insulating said cap from said shell contact, said sleeve also extending inwardly far enough to prevent accidental contact to said shell contact when the plug is inserted in a receptacle.

11. A magazine fuse plug comprising an insulating base having a plurality of longitudinally extending passages, fuses extending longitudinally of said passages, an insulating sleeve surrounding said base for covering said passages, an insulating disk extending across the end of said base for closing the ends of said passages, and center contact means for securing said disk to said base.

In witness whereof, we have hereunto subscribed our names.

REUBEN B. BENJAMIN.
ERNST G. K. ANDERSON.
